US0D1068631S

(12) **United States Design Patent** (10) **Patent No.:** **US D1,068,631 S**
(45) **Date of Patent:** **** Apr. 1, 2025**

(54) **CAR STORAGE DEVICE**

(71) Applicant: **Shanghai Yinshi Network And Technology Co., Ltd**, Shanghai (CN)

(72) Inventor: **Lei Song**, Shanghai (CN)

(73) Assignee: **Shanghai Yinshi Network And Technology Co., Ltd**, Shanghai (CN)

(**) Term: **15 Years**

(21) Appl. No.: **29/890,401**

(22) Filed: **Apr. 24, 2023**

(51) LOC (15) Cl. **12-16**

(52) U.S. Cl.

USPC **D12/416**
